UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

AUTOMOBILE AIR CLEANER.

Application filed May 4, 1925. Serial No. 27,855.

My invention relates to means for cleaning the air that is drawn into the carburetor of internal combustion engines, more particularly automotive engines.

5 The object of the invention is to overcome these difficulties and to provide a compact, simple, relatively cheap, and very efficient air cleaner for automotive engines, and in particular, an air cleaner which shall first 10 reliably collect and separate the dust and then automatically eject it so that the device may operate for an indefinite period without care or special attention.

The invention will be readily understood 15 on reference to the drawings that form part of this specification; and in which Fig. 1 is a side elevation of an automotive engine equipped with an air cleaner embodying my invention; Fig. 2 is an enlarged vertical section of the air cleaner proper; Fig. 3 is a 20 horizontal section on the line 3—3 of Fig. 2; Fig. 4 is a horizontal section on the line 4—4 of Fig. 2; Fig. 5 illustrates a modified form which may be adopted, on the line 4—4 25 of Fig. 2; and Figs. 6 and 7 show that the air cleaner may be used in inverted and in horizontal positions.

Referring to the drawing, the block 1 represents the internal combustion engine of 30 which 2 is the manifold and 3 a typical carburetor. At the intake 4 of the carburetor, wherever positioned, is the air cleaner 5 about to be described in detail. A water cooling radiator appears at 6, and 7 represents the engine cooling fan. The part 8 35 represents a small air pressure pipe connected with the cleaner 5 and leading from an air blast receiving cone 9 behind the fan. The device 5 is a centrifugal separator which 40 stands at the entrance of the carburetor. To reach the carburetor the air must pass through it, and in passing through it the air is caused to whirl rapidly in a plane that is transverse to the axis upon which the air 45 enters the carburetor. In consequence of the whirling motion the dust is centrifugally separated. Next, the separated dust is whirled forward and expansively ejected into a groove or race 10. Whirling therein 50 the dust flies outward and is ejected through a tangential discharge nozzle 11 at the periphery of the groove 10. The pipe 8 enters directly opposite the discharge opening or nozzle 11 and the small blast of air received through the cone at the front end of

the pipe 8 by its force so augments the centrifugal force of the dust particles as to successfully and continuously eject the latter from the nozzle 11.

Interesting details of the construction 60 comprise the annular member 12 which contains the expansion groove 10. The smaller opening 13 in the member 12 fits and registers with the intake of the carburetor, whatever its form. The larger opening 14 in the 65 member 12 receives the open end of the tangential tuyère ring 15. The latter is characterized by a plurality of narrow slit-like tangential tuyères 16 formed between the tangential blades 17. The end of the tuyère 70 ring may be secured to the member 12 by any suitable means as by brazing it thereto. The opposite end of the tuyère ring 15 is closed by a plug or disk 18, so that the tangential tuyères 16 are the only openings through 75 which the air may pass. Lest a drop of pressure be suffered it is characteristic of my invention that the aggregate area of the tuyères 16 equals, and indeed considerably exceeds, the area of the outlet opening 14. 80 It is further characteristic that the whirling velocity attained with a tuyère area very much in excess of the opening 14 is fully adequate to the accomplishment of the described 85 centrifugal separation.

It will at once be noted that the air cleaner of my invention is extremely small and compact, of very light weight, and generally avoids the objections to the air cleaning devices and apparatus hitherto devised.

The more direct the impact of the column of expelling air from the passage 19 the better will be the automatic ejection of the dust through the nozzle 11. An improvement in this regard may be accomplished by 90 offsetting the drill by which the aligned passages 19 and 11 are made. By offsetting the same as illustrated in Fig. 5 the gap or opening 19 into the side of the groove 10 may be shortened. Obviously, an ample opening remains for the discharge of the dust from the race or groove 10 and yet the ends of the passages 19 and 11 are brought so close together that the swiftly moving column of air drawn in at 19 immediately impacts and thrusts against the end of the column in the passage 11 and markedly expedites the ejection of the latter.

It will at once be apparent that the herein described "cross-shot" method of expediting

and accomplishing the peripheral discharge or eject of a centrifugal separator is not limited to operation by pressure air derived from a fan 6, but lends itself to operation by 5 any pressure fluid.

The centrifugal force developed within the centrifugal separator is so great that it can almost be relied upon to automatically eject the heavier substances. The augmenting forces that need be delivered through the "cross-shot" passage b'' or b^x is so slight that only a very low pressure of air or gas need be maintained at the intake end of the "cross-shot" passage.

15 It goes without saying that this air cleaner is adapted for attachment to the intakes of air compressors, small blowers, and the like; wherever it is desirable to clean the intake air.

20 Having thus described my invention I claim as new and desire to secure by Letters Patent:—

1. An air cleaner for internal combustion automotive engines, and the like, comprising 25 a centrifugal dust separator for association with the engine intake, and having at one end a tangential peripheral dust outlet, in combination with means for maintaining an auxiliary movement of an ejector fluid 30 first into said end of the separator and

thence into said outlet and in the direction of the dust discharge.

2. An air cleaner for internal combustion automotive engines and the like, comprising a multiple tangentially tuyèred barrel in combination with a closure at one end of said barrel, a partial closure at the other end of said barrel, said partial closure containing the outlet opening, and peripheral race, said race having a tangential dust discharge opening at one side and an eject pressure nozzle entering said race in substantial alignment with said dust discharge opening.

3. An air cleaner for internal combustion automotive engines and the like, comprising 45 a multiple tangentially tuyèred barrel in combination with a closure at one end of said barrel, a partial closure at the other end of said barrel, said partial closure containing the outlet opening, and a peripheral race, said race having a tangential dust discharge opening at one side and an eject pressure nozzle entering said race in substantial alignment with said dust discharge opening, and means for supplying a pressure fluid to said nozzle.

In testimony whereof I have hereunto set my hand this 30th day of April, A. D. 1925.

CHARLES GILBERT HAWLEY.
